WINDOW GUARD

Kurt Tschaepe, New York, N. Y.

Application April 10, 1939, Serial No. 267,084

2 Claims. (Cl. 20—71)

This invention relates to a window guard for preventing persons from falling from the window, the general object of the invention being to provide a guard which is adjusted to be fastened to the inside of a window frame or wall, said guard being so formed that it can be moved from the inside of a window to the outside thereof and moved back to the position inside of a window without the operator moving outside of the window. When the guard is located at the inside of the window it will prevent persons from falling through the window and when located outside of the window it will prevent window cleaners and other persons working outside of the window from falling therefrom.

Another object of the invention is to provide latch means for holding the parts in adjusted position.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary view looking toward a window and showing the invention in use therein with the device in position extending across the lower part of the window opening.

Figure 2 is a similar view but showing the device in position extending from the outer part of the window.

Figure 3 is a section on the line 3—3 of Figure 2.

Figure 4 is a section on the line 4—4 of Figure 2.

Figure 5 is a section on the line 5—5 of Figure 1.

Figure 6 is a fragmentary longitudinal sectional view showing the latch means for connecting one bar to another bar and this view also showing the means for pivotally connecting one bar to a stationary bar.

Figure 7 is a section on the line 7—7 of Figure 5.

Figure 8 is a section on the line 8—8 of Figure 6.

Figure 9 is a view of one of the pivotal lugs.

Figure 10 is a detail view showing a modification.

In carrying out the invention a pair of elongated flat bars 1 are fastened to the side mem-

bers of a window frame by bolts 2 and a lug 3 extends outwardly from the central part of each bar into the window opening. Each lug has an annular groove 4 therein into which extends a beveled projection 5 which is formed by terminating the ends of the groove in spaced relation.

A pair of arms 6 each has a cylinder 7 attached to one end and these cylinders fit over the lugs 3 and each cylinder has an internal projection 8 fitting in the groove 4. Thus the arms 6 are pivotally supported on the lugs 3 and these projections 5 and 8 permit the arms to be swung in an arc of 270 degrees.

The other ends of the arms 6 are connected to a second pair of arms 9 by the bolts 10 and nuts 11, the two bolts being placed in a spacer 11 which extends between the arms 9 and the bolts 10 are fastened in the spacer by the rivets 12. The two arms 9 are connected together by the cross members 13 which may also be elongated bolts passing through spacers. The outer end of each arm 6 is of substantially circular shape as shown at 14 but provided with the stop shoulders 15 and the adjacent end of each arm 9 is formed with an arcuate flange 16 which slides over the arcuate part 14 but is limited in its movement by the stop shoulders 15. These parts are so arranged as to permit each arm 9 to be moved from a position overlying an arm 6 to a position where the arm 9 extends at right angles to the arm 6.

The projections 5 and 8 are so arranged as to permit the arms 6 to extend vertically downwardly at the inner part of the window opening as shown in Figure 1 and then to be moved upwardly and outwardly to a position where the arms 6 extend horizontally through the window opening as shown in Figure 3. When the guard is in position extending across the lower portion of the window opening as shown in Figure 1 the frame composed of the parts 9 and 13 extends substantially parallel with the arms 6 as shown in Figure 1 so as to prevent anyone falling through the window and in this position of the parts the arms 6 cannot move outwardly through the window opening due to the stops 5 and 8 being in engagement. When the arms 6 are moved upwardly and outwardly to the position shown in Figure 3 the arms 9 and the cross bars 13 are swung downwardly and outwardly to the position shown in Figure 3 and when the parts reach this position, the arms 6 are locked in the horizontal position shown in Figure 3 by means of latch pins 17 projected by springs through holes 18 in the cylinders 7 and into holes 19 in

the lugs 3 when said arms 6 are moved to the horizontal position as shown in Figure 3. Each pin 17 is carried by a cross piece 20 having the rods 21 attached thereto which pass through 5 holes in the stationary cross piece 22 on each arm 6 and the springs 23 act to project the pin 17 into the holes 18 and 19. The cross piece 20 is beveled as at 20' and when each arm 9 is swung to a position over an arm 6 an angle lug 10 25 on said arm 9 will engage the bevel 20' and thus force the latch pin 7 out of the holes so as to release the arms 6 to permit them to be swung on the pivots. When an arm 9 is in overlapping position on an arm 6 a latch pin 27 15 on a spring plate 28 carried by an arm 6 engages a hole 29 in an arm 9 to lock the two sets of arms together in overlapping relation in the position they occupy in Figure 1 and also in Figure 6. Each pin 27 can be pushed from its hole 29 20 by pressing an object into the hole 29 against the pin 27.

In addition to the bolts 2 for fastening the plates 1 to the side members of the window frame, pins 2' may be used for connecting the 25 supporting members to the window sill by making said members of considerable length as shown in Figure 10 at 1'.

From the foregoing it will be seen that the window guard can be readily moved to the position shown in Figure 1 where it will extend across 30 the lower part of the window opening and the parts are held against outward movement so that the guard will prevent anyone from falling out of the window. Then when a window cleaner is 35 cleaning the windows or the window is to be worked upon from the outside, then the arms 6 are swung upwardly and outwardly, carrying the arms 9 with them until arms 6 reach the horizontal position shown in Figure 3. Then the 40 arms 9 are swung downwardly and outwardly and as the arms 9 leave the arms 6 the members 25 will leave the members 20 so that the springs can project the latch pins 17 into locking position to lock the arms 6 in horizontal position. 45 When the arms 9 reach a vertical position as shown in Figure 3 an end of each flange 16 will engage the stop 15 which will prevent the members 9 from swinging outwardly beyond the vertical position.

50 It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A window guard of the class described comprising supporting members attached to the side members of a window frame, a pair of arms having one end pivotally connected with the supporting members, stop means for limiting swinging movement of the arms to three-quarters of a circle and from a depending vertical position upwardly and inwardly and then outwardly to 15 a horizontal position where the arms extend outwardly through the window opening, a frame including arms pivoted to the free ends of the first-mentioned arms, stop means for limiting movement of the frame on the first-mentioned 20 arms beyond a vertical position when the first-mentioned arms are in outward horizontal position, and spring actuated latch means for locking the first-mentioned arms in said horizontal position extending outwardly from the window 25 as said first-mentioned arms reach said horizontal position.

2. A window guard of the class described comprising supporting members attached to the side members of a window frame, pivot lugs extending 30 outwardly from said supporting members, a pair of arms, cylinders connected with the arms adjacent one end thereof and rotatably arranged on the lugs, means for limiting swinging movement of the arms on the lugs to permit the arms 35 to be placed in a vertical position extending downwardly or in a horizontal position extending outwardly, a frame including arms pivoted to the free ends of the first-mentioned arms, stop means for limiting movement of the frame on the first-mentioned arms beyond a vertical position when the first-mentioned arms are in horizontal position, latch means for locking the first-mentioned arms in horizontal position extending 40 outwardly from the window, and means for automatically releasing the latch means when the frame is swung into parallel position with the first-mentioned arms and latch means for holding the arms of the frame in parallel position 45 with the first-mentioned arms.

KURT TSCHAEPE.
